UNITED STATES PATENT OFFICE

2,384,679

ATOMIZER FOR LIQUID UNDER PRESSURE

Grover B. Holtzclaw, Charlotte, N. C., assignor
to Parks-Cramer Company, Fitchburg, Mass.,
a corporation of Massachusetts

Application November 20, 1944, Serial No. 564,219

11 Claims. (Cl. 299—59)

This invention relates to automatically controllable atomizers for vaporizing liquids and especially to those for delivering moisture to an enclosure to maintain the atmosphere thereof closely at a predetermined uniform condition of humidity.

The general object of the invention is to provide an atomizer of simple and economical construction and capable of long life with a minimum of repairs and which will be more accurately regulated to maintain a desired vaporization of liquid.

More particularly the invention relates to improvements in atomizers of the types disclosed in the patents to Herman F. Simon No. 2,186,214 granted January 9, 1940, for Liquid atomizing devices and No. 2,362,102 granted November 7, 1944, for Self-cleaning atomizer. In the construction disclosed in Patent No. 2,186,214 a jet of liquid is produced by the inspiration of a surrounding jet of air under pressure and the operation of the atomizer is controlled by regulation of the pressure of the atomizing air acting upon a single diaphragm. In atomizers of this type the atomizing air must be maintained at a high pressure to cause inspiration of the liquid and the vaporization thereof.

One of the objects of the invention is to provide an atomizer of the single diaphragm type in which a saving of air consumption and cost of operation is reduced by supplying the atomizer with air and liquid maintained under correlated superatmospheric pressures much less than that required for the operation of atomizers in which the liquid is supplied to the atomizer by inspiration of the surrounding jet of air.

The atomizer disclosed in Patent No. 2,362,102 is adapted to be supplied with liquid and air under correlated superatmospheric pressures which are automatically controlled to maintain the same correlation while the pressures are varied in accordance with the desired amount of vaporization. In that construction air and liquid chambers are respectively provided with yieldable walls, such as diaphragms, the operations of which are controlled by conjoint variations in said correlated pressures to produce the desired amount of atomization of the liquid. Such atomizers are of expensive construction and the object of the present invention is to eliminate certain of the parts thereof and to provide a more accurate operation of the atomizer and also to provide a more simple and efficient means for cleaning the air and water outlets.

The self-cleaning atomizer is disclosed in Pat-

ent No. 2,362,102 as embodied in a system for vaporizing water within an enclosure with regulating means responsive to the condition of humidity of said atmosphere for controlling the correlated pressures of the air and water, thereby to maintain a substantially uniform predetermined condition of humidity of the air of the enclosure. The atomizer of the present invention differs from that disclosed in Patent No. 2,362,102 in that the atomizer comprises a head having an air nozzle and a cooperating liquid nozzle and chambers respectively for air and liquid maintained under correlated superatmospheric pressures adapted to communicate with the respective nozzles and a single resiliently yieldable wall for the liquid chamber with means respectively operable by the movements thereof to control the communication of both the liquid chamber with the liquid nozzle and the communication of the air chamber with the air nozzle in accordance with the liquid pressure, said movements of the diaphragm preferably also being adapted to actuate mechanisms for cleaning both the outlets of the air and liquid nozzle.

Any suitable regulating mechanism may be provided for controlling the operation of the atomizer of the present invention, such for example as that disclosed in the Simon Patent No. 2,362,102 to maintain a desired atomization while maintaining the same correlation of air and liquid pressures during the conjoint variation thereof in response to the humidity requirements of the atmosphere of the enclosure.

A further object of the invention is to provide an atomizer of the character herein described having a single diaphragm actuated by the pressure of the liquid which upon predetermined reduction of pressure will first shut off the communication between the liquid chamber and the liquid nozzle and upon further reduction of the pressure of the liquid will shut off communication of the air chamber with the air nozzle, thereby trapping such air under pressure as remains in the system, thus avoiding the necessity of free blow valves for the air which have heretofore been required to prevent dripping of liquid from the atomizer, and thereby enabling the atomizer more promptly to resume operation upon increase in liquid pressure above said predetermined amount, and consequently effecting a still further saving in air consumption and cost of maintenance of operation.

Where liquid under superatmospheric pressure is supplied to an atomizer the orifice of the liquid nozzle is necessarily smaller and inasmuch as

even the best drinking water contains chemicals and occasionally dirt the smaller orifice becomes more easily clogged and requires more frequent and efficient cleaning and the present invention therefore embodies more efficient means for cleaning the nozzle orifice.

Another object of the invention is to provide simplified mechanism operated by the movement of the single diaphragm which is subject to liquid pressure which upon predetermined reduction of the liquid pressure will successively discontinue the jet of liquid and the surrounding jet of air and successively clean the small orifice of the liquid nozzle and the liquid nozzle.

Another object of the invention is to provide a construction in which the flexing of the diaphragm is decreased and a smaller area of the diaphragm subjected to wear, thus prolonging its active life.

Inasmuch as atomizing air which is continuously supplied to the atomizer by a compressor carries with it some oil and vapors which are detrimental to rubber contained in the diaphragms one of the features of the invention is to minimize such detrimental effect by causing the actuation of the single diaphragm by the liquid and in which the opposite side of the diaphragm is in contact with a confined body of air which contains no oil or other vapors, thereby prolonging the life of the single diaphragm which controls the operation of the atomizer.

These and other objects and features of the invention will more fully appear from the following description and the accompanying drawing and will be particularly pointed out in the claims.

A preferred form of atomizer embodying the invention is illustrated in the accompanying drawing, it being understood that the mechanism for automatically controlling the operation of the diaphragm may be similar to that disclosed in Patent No. 2,362,102, and need not be illustrated herein.

In the drawing:

Fig. 1 is an enlarged view, mainly in vertical longitudinal section, of a preferred form of atomizer showing the parts thereof in non-atomizing self-cleaning positions; and,

Fig. 2 is a similar view of the atomizer shown in Fig. 1, showing the parts thereof in atomizing position.

A preferred form of atomizer for supplying moisture to the atmosphere of an enclosure, which is illustrated in the drawing, is of pear-shape streamline construction comprising a main body portion 1 and a hollow rear body portion 2 joined to it by a screw threaded connection 3 and a cap 4 which is screwed upon a hollow cylindrical extension 5 of the body 1 provides an air chamber 6. The cap 4 has an inwardly tapering conical outlet 7 terminating in an annular shoulder 8. A disk 9 is clamped between the shoulder 8 and the end of the extension 5 and is provided with a central outlet 10 forming a nozzle communicating with the air chamber 6.

Desirably the disk 9 is held in the cap 4 by a spring ring 11 which when the cap is assembled upon the extension is received in a peripheral recess in the extension. The main body portion 1 has a downwardly extending screw threaded extension 12 adapted to be connected by a suitable union to a conduit for air under pressure and a suitable passage 13 leads from said extension to the air chamber 6. The rear portion of the body 1 is hollowed out to provide a liquid chamber 14 and the body is provided with an aperture 15 hav-

ing a screw threaded wall adapted to receive a suitable union 16 by which it may be connected to a pipe for supplying liquid under pressure to the chamber 14.

5 The chamber 14 of the atomizer is provided with a resiliently yieldable wall adapted to be actuated by the pressure of the liquid in the liquid chamber. Means, operable by said yieldable wall, 10 controls the communication between the liquid chamber and a suitable liquid nozzle and also controls the communication between the air chamber and the air nozzle.

In the preferred embodiment of the invention illustrated herein the rear wall of the liquid chamber is in the form of a diaphragm 17, which is peripherally clamped in the joint between the main body 1 and the rear body portion 2, the rear body portion being provided with a chamber 18 complementary to the liquid chamber 14 to 15 permit flexure of the diaphragm.

Suitable resilient means are provided for backing the yieldable wall of the liquid chamber against the pressure of the liquid therein. In the construction illustrated a hollow cylindrical plunger 19, which is slidably mounted in a cylindrical bore in the rear body portion 2 of the atomizer, is provided with a head 20 which engages the rear face of the diaphragm 17 and is backed by a strong spring 21 the opposite end of which is seated upon 20 a cylindrical block 22 which abuts a preferably convergingly tapering end wall of the bore of the rear body member 2 of the atomizer.

An internally screw threaded nut 23 abuts the head 20 of the plunger 19 and has a cylindrical extension 24 which passes through the block 22 and is provided with a reduced screw threaded end portion having a nut 25 which is adapted to engage the block 22 and limit the forward movement of the plunger produced by the spring 21. The head 20 of the plunger has an annular flange 26 which upon rearward movement of the plunger is adapted to engage the shoulder 27 of an annular internal recess in the rear body member 2 to limit the rearward movement of the plunger.

45 The diaphragm 17 is clamped upon the head 20 of the plunger by a bolt having a preferably circular head 28 and a screw threaded stem 29 which engages the internal screw threads of the nut 23, the head 28 being provided with flattened faces 30 50 adapted to be engaged by a suitable tool and rotated to clamp the diaphragm on the plunger head.

The head of the bolt is provided with a conical extension 31 forming a valve for controlling the 55 communication between the liquid chamber and a liquid nozzle 32 through which the jet of liquid under pressure is projected.

The nozzle 32, which preferably is of cylindrical form, is slidably mounted in a hub 33 in the main body portion of the atomizer in axial alignment with the air nozzle 10, and has a conically converging end portion 34 which terminates in a cylindrical tip 35 adapted to penetrate, clean and close the air nozzle. The tip portion of the liquid nozzle is provided with a very small outlet 36 which communicates with a larger cylindrical bore 37 in the tapering portion which in turn communicates with a further enlarged cylindrical bore 38, the rear end of which communicates with the liquid chamber.

The rear end of the liquid nozzle 32 is provided with a conical valve seat 39 complementary to the conical valve 31 which is mounted upon the diaphragm 17. The cylindrical portion of the liquid nozzle has a peripheral flange 40 which

is adapted to engage the rear wall of the air chamber 6 and limit the rearward movement of the liquid nozzle to atomizing position, as illustrated in Fig. 2. A rearward converging light spring 41, which is seated upon the disk 9, engages the flange 40 of the liquid nozzle 32 and tends to force the nozzle rearwardly thereby to maintain the valve seat at the rear end thereof in engagement with the valve 31 until rearward movement of the nozzle is arrested by engagement of its flange 40 with the rear wall of the air chamber 6.

Suitable means are provided for cleaning the small outlet of the liquid nozzle when the pressure in the liquid chamber is reduced to a predetermined amount. In the preferred construction illustrated herein the valve 31 is of truncated conoidal form and a cylindrical cleaning rod 42, which is secured to or integral with the truncated end thereof, is slidably mounted in the larger cylindrical bore of the liquid nozzle and is provided with a slotted-off portion or portions 42a to permit flow of liquid from the liquid chamber through the nozzle when the nozzle is in atomizing position.

The rod 42 is provided with a reduced cylindrical end portion 43 adapted to fit the enlarged bore 37 of the nozzle and a cleaning wire 44, which is mounted in the end thereof, is adapted to penetrate and clean the small outlet 36 of the liquid nozzle upon predetermined reduction of the pressure in the liquid chamber 14.

In the operation of the atomizer—assuming that the parts are in the position shown in Fig. 1 in which the liquid nozzle penetrates and closes the air nozzle and the inlet port of the liquid nozzle is closed by the valve 31 under the influence of the spring 21 which backs the yieldable wall of the liquid chamber—when air and liquid under correlated superatmospheric pressures are introduced into the respective chambers of the atomizer, the resiliently yieldable wall of the liquid chamber will be forced rearwardly against the pressure of the spring 21. At the same time the light spring 41 will force the liquid nozzle rearwardly maintaining the inlet port thereof in closed engagement with the valve 31 and the outlet of the liquid nozzle also closed by the cleaning rod and the wire thereof which extends through the liquid nozzle until the flange 40 of the liquid nozzle engages the shoulder at the base of the air chamber 6 and the liquid nozzle is then in atomizing position with air under pressure flowing through the air outlet 10. Further increase in pressure in the liquid chamber will force its yieldable wall rearwardly, thereby removing the valve 31 from engagement with the port 39 of the liquid nozzle and withdrawing the cleaning rod and its cleaning wire from the outlet of the liquid nozzle, thus permitting a jet of liquid to be projected from the nozzle axially toward the air nozzle outlet. So long as sufficient pressure of the liquid is maintained in the liquid chamber the atomizer will continue to operate.

However, when such predetermined reduction of pressure of the liquid as will enable the spring 21 to force the liquid nozzle forwardly occurs, the valve 31 will engage the valve seat 39 of the liquid nozzle, thereby shutting off the supply of liquid from the liquid chamber to the liquid nozzle and cause the cleaning wire to penetrate and clean the small outlet of the liquid nozzle. Upon continued reduction of the pressure of the liquid, the heavy spring 21 will force the slideable liquid nozzle forwardly against the pressure of the

lighter spring 41 until the tip of the liquid nozzle penetrates, cleans and closes the air nozzle outlet. By reason of this construction the delivery of liquid from the liquid chamber to the liquid nozzle is shut off in advance of the discontinuance of the delivery of air under pressure from the air chamber through the air nozzle, thus preventing dripping of the atomizer.

When in the operation of the device in a humidifying system communication between the liquid chamber and the liquid nozzle and the air chamber and the air nozzle are successively discontinued upon predetermined reduction in pressures, some pressure remains on the water in the system and air under pressure is trapped in the system when the operation of the humidifier is discontinued so that when air and liquid under higher correlated pressures are supplied to the respective air and liquid chambers, atomization is more promptly established than in usual systems in which free-blow valves in which the conduit for the air under pressure is provided with a free-blow valve. This also results in reducing the amount of power required to replace the air wasted through the free-blow valve. A more accurate control of atomization is effected by the present invention, than in atomizers heretofore produced, by reason of the fact that the movements of the diaphragm, or other yieldable wall of the liquid chamber, and the mechanism operated thereby, is actuated by variations in the pressure of a liquid which is non-compressible as distinguished from the actuation thereof by air which is highly elastic and therefore not capable of effecting such prompt and accurate transmission or variations in air pressure to the yieldable wall. As a consequence, more accurate regulation of atomization in a humidifying system is maintained in accordance with the humidity requirements of the atmosphere of the enclosure.

By actuating the means for cleaning the air and liquid nozzles respectively from the movements of the single yieldable wall of the liquid chamber in sequence with the shutting off of the communication between the liquid chamber and the liquid nozzle and the air chamber and air nozzle respectively, prompt and effective cleaning of the nozzle outlets is insured.

By thus utilizing the relative movements of the single yieldable wall of the liquid chamber to actuate the liquid nozzle and the cleaning mechanism an economical construction is provided and by actuating the single diaphragm the atomizer by liquid pressure instead of air pressure longer life of the atomizer is insured than if the diaphragm were operated by air pressure.

It will therefore be apparent that numerous advantages are obtained over previous atomizer constructions.

While in the particular embodiment of the invention illustrated herein the yieldable wall of the liquid chamber is in the form of a diaphragm it may be otherwise constructed as, for example, in the form of a resiliently backed plunger slidably fitting the bore of the rear portion of the atomizer head and provided with a valve and cleaning mechanism of the character described, or may be otherwise constructed to accomplish the purposes herein set forth.

It will also be understood that while air for atomizing liquid for humidifying the air of an enclosure has been particularly described herein, that steam or other gaseous fluid under pressure correlated to the pressure of the liquid may be

employed within the meaning of the following claims.

Finally, it will be understood that the particular embodiment of the invention herein shown and described is of an illustrative character and that various modifications in construction and arrangement of parts may be made within the meaning and scope of the following claims.

Having thus described the invention, what is claimed as new, and desired to be secured by Letters Patent, is:

1. An atomizer comprising a head having an air nozzle and a cooperating liquid nozzle and chambers respectively for air and liquid maintained under correlated superatmospheric pressures acting when in communication with the respective nozzles to supply air and liquid thereto, and a single resiliently yieldable member forming a wall of the liquid chamber and means respectively operable by the movements thereof to control both the communication of the liquid chamber with the liquid nozzle and the communication of the air chamber with the air nozzle in accordance with the liquid pressure.

2. An atomizer comprising a head having an air nozzle and a cooperating liquid nozzle slidably mounted in axial alignment therewith and chambers respectively for air and liquid maintained under correlated superatmospheric pressures acting when in communication with the respective nozzles to supply air and liquid thereto, and a resiliently backed diaphragm forming a wall of the liquid chamber, and means respectively operable by the movements thereof to control both the communication of the liquid chamber with the liquid nozzle and the communication of the air chamber with the air nozzle in accordance with the liquid pressure.

3. An atomizer comprising a head having an air nozzle and a cooperating liquid nozzle slidably mounted in axial alignment therewith and chambers respectively for air and liquid maintained under correlated superatmospheric pressures acting when in communication with the respective nozzles to supply air and liquid thereto, a resiliently backed diaphragm forming a wall of the liquid chamber having means cooperating with said slidable liquid nozzle acting to control the communication of the liquid chamber with the liquid nozzle and the communication of the air chamber with the air nozzle in accordance with the liquid pressure and upon predetermined reduction of said liquid pressure first to shut off communication of the liquid chamber with the liquid nozzle and thereafter to shut off communication of the air chamber with the air nozzle.

4. An atomizer comprising a head having a chamber for air under superatmospheric pressure provided with an air nozzle, a chamber for a liquid maintained under correlated superatmospheric pressure, a liquid nozzle slidably mounted in said head in axial alignment with said air nozzle having at one end means to close said air nozzle and at its other end an inlet port communicating with said liquid chamber, a single diaphragm forming a wall of the liquid chamber and having a valve for said inlet port movable to open position by said diaphragm in response to the liquid pressure in said liquid chamber, and resilient means acting upon said diaphragm operable upon predetermined reduction of said liquid pressure to cause the valve to close said inlet port and thereafter to cause the liquid nozzle to close said air nozzle.

5. An atomizer comprising a head having an air nozzle and a cooperating liquid nozzle and chambers acting when in communication with the respective nozzles to supply air and liquid under pressure thereto, a diaphragm forming a wall of the liquid chamber, a cleaning member for said air nozzle, a cleaning member for said liquid nozzle and means acting upon said diaphragm operable upon predetermined reduction of said liquid pressure to actuate the cleaning members and clean both the air nozzle and the liquid nozzle.

6. An atomizer comprising a head having an air nozzle and a cooperating liquid nozzle and chambers acting when in communication with the respective nozzles to supply air and liquid under pressure thereto, a diaphragm forming a wall of the liquid chamber, a cleaning member for said air nozzle, a cleaning member for said liquid nozzle and a spring acting upon said diaphragm to actuate the cleaning members to clean both the air nozzle and the liquid nozzle.

7. An atomizer comprising a head having an air nozzle and a cooperating liquid nozzle and chambers acting when in communication with the respective nozzles to supply air and liquid under pressure thereto, a diaphragm forming a wall of the liquid chamber, a cleaning member for said air nozzle, a cleaning member for said liquid nozzle connected to said diaphragm, and a spring acting upon said diaphragm to actuate the cleaning members and clean both the air nozzle and the liquid nozzle.

8. An atomizer comprising a head having an air nozzle and a cooperating liquid nozzle and chambers respectively for air and liquid maintained under correlated superatmospheric pressures acting when in communication with the respective nozzles to supply air and liquid thereto, a diaphragm forming a wall of the liquid chamber, a cleaning member for the air nozzle, a cleaning member for the liquid nozzle, and means acting upon said diaphragm operable upon predetermined reduction of said liquid pressure to actuate both the cleaning members and clean respectively the air nozzle and the liquid nozzle.

9. An atomizer comprising a head having a chamber for air under superatmospheric pressure provided with an air nozzle, a chamber for liquid maintained under correlated superatmospheric pressure, a liquid nozzle slidably mounted in said head having at one end means to penetrate, clean and close said air nozzle and having at its other end an inlet port communicating with said liquid chamber, a single diaphragm forming a wall of said liquid chamber having a valve for said inlet port and provided with a cleaning member for said liquid nozzle movable by said diaphragm in response to said liquid pressure to open said valve and withdraw the cleaning member from the outlet of the liquid nozzle, and resilient means acting on said diaphragm operable upon predetermined reduction of said liquid pressure to cause the valve to close said inlet port and to cause the cleaning member thereafter to penetrate and clean the outlet of the liquid nozzle.

10. An atomizer comprising a head having a chamber for air under superatmospheric pressure provided with an air nozzle, a chamber for liquid maintained under correlated superatmospheric pressure, a liquid nozzle slidably mounted in said head having at one end means to penetrate, clean and close said air nozzle and having at its other end an inlet port communicating with said liquid chamber, a single diaphragm forming a wall of

said liquid chamber having a valve for said inlet port provided with a cleaning member for said liquid nozzle movable by said diaphragm in response to variations in said liquid pressure, resilient means acting upon said liquid nozzle during the preliminary admission of liquid under pressure to said liquid chamber to hold the inlet port of said liquid nozzle in engagement with said diaphragm valve, means for arresting said nozzle when in atomizing position to permit opening of said valve by further movement of said diaphragm, and resilient means acting upon said diaphragm operable upon predetermined reduction of said liquid pressure to cause said valve to close said inlet port and the cleaning member to penetrate and clean the outlet of the liquid nozzle and thereafter to cause said liquid nozzle to penetrate, clean and close said air nozzle.

11. An atomizer comprising a head having an

air nozzle and a co-operating liquid nozzle and chambers respectively for air and liquid maintained under correlated atmospheric pressures acting when in communication with the respective nozzles to supply thereto liquid and air for atomizing the liquid, means for controlling the communications between the respective air and liquid chambers and their respective nozzles, means for conjointly actuating the respective controlling means comprising only a single diaphragm in said head forming a yieldable wall for the liquid chamber, subject to variations in the pressure of the non-compressible liquid, and a spring backing said wall located in a chamber in said head containing air free from oil or vapors detrimental to the material of the diaphragm which would shorten the life thereof.

GROVER B. HOLTZCLAW.
